UNITED STATES PATENT OFFICE.

GEORGE CALLAS, OF WASHINGTON, DISTRICT OF COLUMBIA.

DESIGN FOR A FLOWER VASE.

Application filed October 31, 1924. Serial No. 11,238. Term of patent 14 years.

To all whom it may concern:

Be it known that I, GEORGE CALLAS, a citizen of Greece, residing at Washington, District of Columbia, have invented a new, original, and ornamental Design for Flower Vases, of which the following is a specification, reference being had to the accompanying drawing, forming part thereof.

I claim:

The ornamental design for a flower vase, as shown.

GEORGE CALLAS.
